MANUFACTURE OF THIOPHENOLS

Everett E. Gilbert and Emery J. Levin, New York,
N. Y., assignors to Allied Chemical & Dye Corporation, a corporation of New York

No Drawing. Application October 29, 1946,
Serial No. 706,504

7 Claims. (Cl. 260—609)

1

This invention relates to the production of thiophenols and is particularly concerned with improvements in the reduction of di-aryl polysulfides whereby thiophenols may be obtained easily and by means of inexpensive reagents.

In the past it has been proposed to produce thiophenols by reduction of di-aryl disulfides employing various reducing agents such as sodium, metallic zinc in acidic media, electrolytic reduction, and the like. Such processes have been suitable for laboratory production of thiophenols but involve relatively expensive reagents and complex procedures and accordingly are not capable of producing thiophenols at low cost.

One object of the present invention is to provide an inexpensive process for making thiophenols by means of chemical reduction employing easily available reducing agents. A further object of the invention is to provide a simple procedure for the production of thiophenols, which eliminates the numerous steps required by the complex procedures of the prior art. A further object of the invention is to provide a process applicable to the reduction of di-aryl disulfides and di-aryl polysulfides of higher sulfur content such as the polysulfide mixtures obtained by reacting diphenyl disulfide with sulfur or by reacting diphenyl sulfone with sulfur to produce polysulfide mixtures having an average sulfur content in the neighborhood of 4 to 6 sulfur atoms per molecule. Still further objects of the invention will be apparent from the following description and illustrative examples.

In accordance with the invention, a di-aryl polysulfide (which term is used to include the disulfide as well as higher sulfides) is heated with a petroleum hydrocarbon material boiling above 250° C., the heating step being carried out at temperatures of at least 250° C. rising finally to between 350° C. and 400° C.

The process of the invention is applicable to the manufacture of thiophenols from unsubstituted and substituted di-aryl polysulfides; e. g., diphenyl, ditolyl, dixylyl, dicumenyl, dipseudocumenyl, dinaphthyl, dianthranyl, dibiphenyl, dichlorophenyl, di-o-dichlorophenyl, di-1,2,4-trichlorophenyl, di-m-chlorotolyl, di-2,4-dichlorotolyl, and di-chloro-p-xylyl polysulfides.

The proportion of petroleum hydrocarbon material to be employed as reducing agent is quite flexible and since it is a relatively cheap material, it is advantageous to employ an excess. In the case of diphenyl polysulfides weight ratios between about one part and about 8 parts of the reducing agent for each 4 parts of polysulfide are

preferred. In the case of the homologs, such as the dicumenyl polysulfides, ratios of reducing agent to polysulfide in the upper portion of the specified range are preferred and higher ratios may be advantageous.

When a thiophenol volatile at the reaction temperatures is being produced, the thiophenol may be distilled off from the reaction mixture and recovered by condensation. Removal of the thiophenol during the reaction avoids pyrolysis of the product and consequently leads to higher yields than obtainable by carrying out the heating step without removing the product.

In the process of the invention the high-boiling petroleum hydrocarbons act as reducing agents converting sulfur in the polysulfide to hydrogen sulfide and providing the hydrogen atom necessary for addition to the thio-aryloxy radical (RS⁻) to convert it to thiophenol. It will be appreciated that the aryl radicals of the di-aryl polysulfides and thiophenols may themselves serve as reducing agents in the process. Such action is to be avoided, however, since it consumes a portion of the aryl radicals present in the polysulfide and results in correspondingly smaller yields of thiophenols.

In general, low-boiling hydrocarbons are relatively unsatisfactory reducing agents for the purpose compared to the high-boiling petroleum derivatives employed in accordance with the invention, and furthermore because of the relatively high vapor pressure of such compounds and their dehydrogenation products, tend to contaminate the thiophenol product. For instance, whereas yields above 60% of theoretical may be consistently obtained using the reducing agents of the invention in the manufacture of thiophenol, a similar procedure using the relatively low-boiling hydrocarbon tetralin as a reducing agent resulted in a yield of only 30%, or only 5% to 10% greater than the 20% to 25% conversion obtainable without any added reducing agent. Moreover, as a result of dehydrogenation of the tetralin the product was found to be contaminated with substantial proportions of naphthalene.

While the invention is not limited to petroleum hydrocarbon materials of any particular type, it is preferred to employ those of the paraffinic or naphthenic or mixed base crudes.

Examples of suitable hydrocarbon materials for use in accordance with the invention are No. 6 fuel oil (a petroleum distillation residue not distillable at atmospheric pressure without decomposition and having an initial boiling point

3

of about 310° to 320° C. with some decomposition), petrolatum, paraffin wax, and Pennsylvania Grade crude steam distillation residue. In general these materials comprise complex mixtures of hydrocarbons boiling substantially above 250° C. Paraffin wax, which is usually recovered from a condensate obtained in the steam distillation of petroleum, may contain small proportions of lower boiling materials but for the most part comprises normally solid high-boiling hydrocarbon compounds.

In the following discussion the invention is considered in particular relation to the manufacture of thiophenol from diphenyl polysulfides. It will be understood, however, that the general principles involved are applicable to the manufacture of thiophenols from the other di-aryl polysulfides also.

The process of the invention is effective for the reduction of diphenyl disulfide to thiophenol to obtain high yields in the neighborhood of 80% of theoretical. It is also applicable to the reduction of diphenyl polysulfides containing more than 2 atoms of sulfur per molecule to produce thiophenol in good yields. Representative polysulfides of this type are obtained by heating diphenyl monosulfide with sulfur in a ratio of about 4 atomic equivalents of sulfur per mol of the monosulfide at a temperature of 290° to 330° C. for 1½ hours and then distilling off unreacted diphenyl monosulfide in vacuo to provide a polysulfide residue of approximately the composition $(C_6H_5)_2S_{5\frac{1}{2}}$, or by reacting diphenyl sulfone with about 4 atomic equivalents of sulfur per mol at temperatures of 310° to 330° C. to provide a diphenyl polysulfide having the approximate average molecular formula $(C_6H_5)_2S_4$. The process may be applied to crude polysulfide mixtures such as the oil obtained by heating benzene with a ¼ mol ratio of sulfur chloride at 60°-70° C. in the presence of ferric chloride, then washing and evaporating excess benzene.

The following examples further illustrate the process of the invention. Proportions are in terms of weight unless otherwise indicated:

Example 1

A mixture of 100 parts of diphenyl disulfide and 25 parts of petrolatum was heated in a still provided with a water-cooled condenser. The 50 temperature of the still rose gradually and at about 270° C. thiophenol began to distill off. Heating and distillation were continued for about one hour, at the end of which period the yield of thiophenol obtained in the condenser amounted to 79% of theoretical based on the diphenyl disulfide employed.

Example 2

A mixture of 146 parts of diphenyl polysulfide $(C_6H_5)_2S_{5\frac{1}{2}}$, obtained by reaction of 93 parts of diphenyl monosulfide and 64 parts of sulfur and topping, as previously described, and 73 parts of petrolatum was heated in a still equipped with a water-cooled condenser. When the temperature rose to 250° C., there was a copious evolution of hydrogen sulfide, and thiophenol began to condense in the condenser. Heating was continued to maintain the distillation of thiophenol, and in about 1½ hours the temperature had risen to 360° C. (vapor temperature) and about 53 parts of thiophenol had been recovered in the condenser. This corresponds to a 48% yield based on total monosulfide used (54% based on polysulfide reacted).

4

Example 3

A diphenyl polysulfide $(C_6H_5)_2S_4$, prepared by reacting one mol of diphenyl sulfone with 4 atomic equivalents of sulfur as previously described was employed. A mixture of about 1130 parts of this polysulfide and 284 parts of petrolatum was heated and distilled for 4½ hours at temperatures rising gradually to about 375° C. The distillate was recovered and subjected to vacuum distillation; 485 parts of thiophenol distillate boiling at 85° to 90° C. at 50 mm. of mercury absolute pressure corresponding approximately to a 55% of theoretical yield was obtained.

Example 4

100 parts of diphenyl polysulfide of the type employed in Example 3 and 50 parts of refined paraffin wax were heated and distilled at atmospheric pressure in a period of 2 hours at a temperature rising from 270° to 360° C. with condensation of distillate. The condensate was redistilled as in Example 3, yielding 46.5 parts of thiophenol corresponding to a yield of approximately 60% of theoretical.

Example 5

For purposes of comparison, a series of tests was made under closely similar conditions involving as reducing agents petrolatum, paraffin wax, and "600W" cylinder oil (Pennsylvania Grade crude steam refined residuum).

The procedure employed was as follows: 100 parts of phenyl polysulfide $(C_6H_5)_2S_4$, (prepared from diphenyl sulfone (1 mol) and sulfur (4 mols) as previously described) and 50 parts of the reducing agent were heated in a still equipped with a Vigreux fractionating column. Hydrogen sulfide started to evolve when the still temperature reached 230° C., and distillate began to form at 250° C. Heating was continued for a 2-hour period during which the still temperature rose to about 380° C. During this period the temperature at the top of the column was maintained between about 100° C. and about 200° C. The crude distillate was redistilled at atmospheric pressure, the fraction distilling at 165° to 180° C. being taken as the thiophenol fraction. The following yields were obtained:

	Per cent
Petrolatum	66
Paraffin wax	63
"600W" cylinder oil	61

55 The same procedure employing 100 parts of No. 6 fuel oil as the reducing agent gave a yield of 71% thiophenol.

We claim:

1. The method of making a thiophenol which comprises heating at a temperature of at least 60 250° C. rising finally to between 350° C. and 400° C. a mixture of a di-aryl polysulfide and a petroleum hydrocarbon material boiling above 250° C. and separating the resulting thiophenol from residual hydrocarbon material.
2. The method of making a thiophenol which comprises mixing a di-aryl polysulfide containing an average of 2 to 5 atoms of sulfur per molecule with at least one-fourth its weight of a petroleum hydrocarbon material distilling above 65 250° C. rising finally to between 350° C. and 400° C. and heating the mixture at a temperature of at least 250° C. and separating the resulting thiophenol from residual hydrocarbon material.
- 70 3. The process of the preceding claim wherein

the heating step is conducted at about atmospheric pressure and at temperatures rising gradually from about 250° C. to a final temperature between 350° C. and 400° C. and the thiophenol is distilled off during the heating step.

4. The method of making thiophenol which comprises heating at a temperature of at least 250° C. rising finally to between 350° C. and 400° C. a mixture of a diphenyl polysulfide and a petroleum hydrocarbon material boiling above 250° C., and removing thiophenol in vapor phase as the thiophenol is formed.

5. The method of making thiophenol which comprises heating at a temperature of at least 250° C. rising finally to between 350° C. and 400° C. a mixture of a diphenyl polysulfide containing an average of 2 to 5 atoms of sulfur per molecule and a petroleum hydrocarbon material boiling above 250° C., and removing thiophenol in vapor phase as the thiophenol is formed.

6. The method of making thiophenol which comprises mixing a diphenyl polysulfide containing an average of 2 to 5 atoms of sulfur per molecule with at least one-fourth its weight of a paraffinic petroleum hydrocarbon material distilling above 250° C. and heating the mixture at

about atmospheric pressure at temperatures rising gradually from about 250° C. to a final temperature between 350° and 400° C., and distilling off thiophenol during the heating process.

7. The method of making thiophenol which comprises mixing a diphenyl polysulfide containing an average of 2 to 5 atoms of sulfur per molecule with from one-fourth to twice its weight of a paraffinic petroleum hydrocarbon material distilling above 250° C. and heating the mixture at about atmospheric pressure at temperatures rising gradually from about 250° C. to a final temperature between 350° and 400° C., and distilling off thiophenol during the heating process.
